US00D342231S

United States Patent [19]

Walker et al.

[11] Patent Number: Des. 342,231

[45] Date of Patent: ** Dec. 14, 1993

[54] CHARGER UNIT FOR A PERISTALTIC INFUSION PUMP

[75] Inventors: Clarence L. Walker, Webster Groves; Richard A. Sunderland, Creve Coeur; Mark A. Davis, O'Fallon, all of Mo.

[73] Assignee: Sherwood Medical Company, St. Louis, Mo.

[**] Term: 14 Years

[21] Appl. No.: 689,597

[22] Filed: Apr. 19, 1991

Related U.S. Application Data

CLAIM

The ornamental design for a charger unit for a peristaltic infusion pump, as shown.

DESCRIPTION

FIG. 1 is a front elevational view of a charger unit for a peristaltic infusion pump showing our new design;

FIG. 2 is a left side elevational view thereof;

FIG. 3 is a rear elevational view thereof;

FIG. 4 is a right side elevational view thereof;

FIG. 5 is a top elevational view thereof; and,

FIG. 6 is a bottom elevational view thereof.

Fig. 2.

Fig. 1.

Fig. 4.

Fig. 3.

Fig. 6.

Fig. 5.
